UNITED STATES PATENT OFFICE

RILEY H. WHITMAN, OF VINCENNES, INDIANA

GRAVE MARKER

Application filed June 6, 1931. Serial No. 542,611.

This invention relates to an improved grave marker constructed for individual usage on a grave in a cemetery or burial ground for identification of deceased persons.

5 In carrying the inventive conception into practice, I have found it expedient and practical to accomplish the desired results by providing a marker in the form of a substantially rectangular box-like device to serve 10 as a simple and economical substitute for a headstone.

The preferred embodiment of the invention comprises a sheet metal body of appropriate ornate configuration and shape, the 15 same being of gradual sloping design and formed in its top with a window through which an identification card is visible.

The principal advantage of the improved device is that of economy of manufacture and 20 sale, as well as simplicity and neatness in design and appearance.

Another feature of the invention is predicated upon the use of a swingably mounted pointed arm which serves as an anchoring 25 stake to maintain the marker securely in place to prevent displacement by the wind and the elements.

Other details and features will become 30 more readily apparent from the following description and drawings.

In the drawings:

Figure 1 is a perspective view of a device constructed in accordance with the present 35 invention.

Figure 2 is a transverse vertical section.

Figure 3 is a longitudinal section.

Figure 4 is a bottom plan view.

As before implied, the marker is generally 40 designated by the numeral 5 and is primarily constructed from sheet metal. In fact, the entire body portion is made from a single sheet of metal which is stamped out to assume a substantially rectangular shape in 45 top plan view, and this body may be said to

comprise a pair of end walls 6, a rear wall 7 and a front wall 8.

The walls 6, 7 and 8 are slanted to the degree shown in Figure 2 and the front wall 8 is somewhat shorter than the rear wall 7 50 so as to cause the marker to assume a forwardly and downwardly inclined position with respect to the grave. The top of the body is formed with a rectangular sight opening surrounded by a correspondingly shaped 55 upstanding bead 9 which defines the outer marginal portion of an ornamental frame.

On its under side this same bead defines a keeper channel. Inward of this bead 9 is a curvate or crimped flange 10 whose free edge is directed outwardly, as shown better in Figure 2. These features 9 and 10 together with the rectangular opening provide 60 a framed sight.

I next call attention to the numeral 11 65 which indicates a card and window clamping member. This is formed from a single sheet of metal having a marginal attaching flange 12, a central depressed portion 13 constituting a card receptacle, and an intervening V-shaped bead 14 which fits telescopically 70 into the channel defined by the superposed bead 9.

It will be noted that the portion 13 is provided along the bottom edge with an elongated card slot 15. The numeral 16 designates a mica or glass panel defining a window and 17 represents an identification card. This is an ordinary card of blank form having the name of the deceased, the date, and 80 other data characteristic of an identification grave marker of this general type.

Incidentally the numerals 18 designate bolts or rivets clamping the marginal flange 12 against the underside of the top portion of 85 the body as shown in Figure 2.

I next call attention to a pivoted arm 19 secured by a pivot rivet as at 20 to the inside of the rear wall 7. The lower end of this is pointed as shown in Figure 3. This arm 90

is foldable from the dotted line position shown in this figure to the perpendicular anchoring position shown in full lines. In the full line position it is adapted to be imbedded in the ground for anchoring the entire marker at the head of the grave.

In practice, the card is filled out and inserted between the glass backing or clamping device in slot designated as 15. Then 10 this marker is set at the head of the grave and anchored in place by means of the foldable stake. This holds the marker firmly in place.

In use, it has been observed that the card 15 rarely gets wet and does not require waterproof ink. The marker will not go down, lean, or become otherwise displaced from its anchored position. It is not gruesome or unsightly. In fact, it improves the appearance 20 of the grave and the general appearance of the cemetery. It is exceptionally light in weight, easy to handle and install, economical in price, yet sturdy in construction.

It may be constructed from tin or other 25 economical material and practically made from two pieces of material namely the body and the clamp. It is shaped and ornamented and otherwise painted and trimmed to lend individuality thereto and to render the device 30 suitable in fulfilling the requirements of an article of this type.

It is thought that the description taken 35 in connection with the drawings will enable a clear understanding of the invention to be had. Therefore, a more lengthy description is thought unnecessary.

While the preferred embodiment of the invention has been shown and described, it is to be understood that minor changes coming 40 within the field of invention claimed will be resorted to if desired.

I claim:

1. A grave marker comprising a substantially hollow open-bottom body constructed 45 of sheet metal and having its top portion formed with a centralized substantially rectangular opening surrounded by a crimped flange and an upstanding bead, the flange and bead defining an ornamental frame, and 50 the underside of said bead constituting a keeper channel, a clamping device comprising a depressed receptacle underlying the sight opening and a marginal attaching flange, said depressed portion being formed 55 with a card slot and the surrounding marginal portion thereof being bent to form a substantially V-shaped clamping bead, said V-shaped bead being received in the channel.

2. A grave marker comprising a substantially hollow open-bottom body constructed 60 of sheet metal and having its top portion formed with a centralized substantially rectangular opening surrounded by a crimped flange, and an upstanding bead, the flange 65 and bead defining an ornamental frame, and

the underside of said bead constituting a keeper channel, a clamping device comprising a depressed receptacle underlying the sight opening and a marginal attaching flange, said depressed portion being formed 70 with a card slot and the surrounding marginal portion thereof being bent to form a substantially V-shaped clamping bead, said V-shaped bead being received in the channel, and a card arranged in said depression and 75 a window forming panel overlying said card an inserted between the aforesaid crimped flange.

In testimony whereof I affix my signature.
